[57] **ABSTRACT**

A method and apparatus for coding and selecting data members such as cards. A plurality of series arranged fields on the data member are coded and sensed in sequence with a special code to represent a number, the field following the last digit of the number being a decimal, which decimal can be placed at any field in the series. An electrical circuit for coding and sensing includes a keyboard connected through a stepping switch to coding and sensing solenoids.

FLOATING DECIMAL CODING SYSTEM

BACKGROUND OF THE INVENTION

This invention relates to the sorting of data members, and in particular it relates to a new and improved code system for use with such members.

In copending U.S. Pat. application Ser. No. 811,826, filed Mar. 31, 1969, a method and apparatus for coding and sorting edge notched cards is disclosed and claimed. The cards normally have a plurality of field positions located along one edge thereof, each field position being notched in accordance with a predetermined pattern to represent a number. For example, there may be five bit positions within each field and each of the 10 digits can be represented by a different group of two of the bit positions. In the operation of the apparatus of the said copending patent application, there is a stage during which the entire pack of cards is moved towards a set of selector bars wherein some of the bars are raised relative to the other bars in accordance with a predetermined selection pattern. The cards to be selected move against the said selected bars a greater distance than the remaining cards since the said selected cards have a notch pattern which agrees with the pattern of the raised selector bars, whereas the remaining cards are blocked by the said selector bars.

However, this conventional coding system has suffered from the disadvantage that it has not permitted complete discrimination between the selected cards and the remaining cards. For example, assume that one wished to select the card coded with the number 4. The code bars representing the number 4 would be raised in one of the fields and all cards having a notched pattern representing the number 4 would move onto these raised selector bars. However, there is nothing to prevent movement onto the bars of cards having other fields notched to represent different numbers. For example, cards representing 40, 400, 4,000, etcetera, would also move onto the desired "4" cards.

Thus, there exists a need for a new and improved system for coding data members such as edge notched cards and the like for permitting complete discrimination between the data members representing the specific selected number and the remaining data members of the group.

SUMMARY OF THE INVENTION

Thus, it is a purpose of this invention to provide a new and improved coding system for use in random selection of selected data members from the remaining data members in a group, which system overcomes disadvantages of the prior art.

This purpose of the present invention is achieved by providing a system including, in addition to the codes representing the separate digits, a further code which represents the decimal point. Moreover, this decimal point may be characterized as a "floating decimal point" since it is capable of being placed in any of the fields of the data member. For example, in coding a data member, one will normally start with the first available or useable field and code successive fields to represent successive digits of the number. With the present invention, the decimal point will always be placed in the field next following the field of the last digit of the number being represented. Thus, for example, when a data member is coded to represent the number 4, then the representation for the number 4 will occupy the first field position and the decimal will then be placed in the second field position. On the other hand, if the data number is coded to represent the number 400, then the decimal will be placed in the fourth field position following representations of "4," "0," and "0" in the first three field positions.

The code for the decimal will normally be different in kind from the codes of the 10 digits. For example, each of the 10 digits can be represented by a different group of two of five possible bit positions within a field. However, the decimal will use three of the five bit positions. Thus, no data cards can move onto the raised selector bars unless they have a decimal code at the same field as the card being selected. This of

course provides a blocking feature which will prevent all cards from moving onto the selector bars except for the cards having the selected number.

Another feature of the present invention includes a means for both encoding and selecting the data members such as the data cards in accordance with the new coding system of the present invention. In the preferred arrangement, each field position includes five bit positions. A set of solenoids is provided for each bit position within each field. The desired digit is introduced at a conventional keyboard and the input is directed to the appropriate field by means of a stepping switch. As each number is entered into the keyboard, the appropriate solenoids are activated at the appropriate field position after which the stepping switch is automatically moved to the next field. As explained in our said previous application, these solenoids actuate selector bars, and after all of the fields have had the necessary selector bars actuated therein, further means on the apparatus either use the selected selector bars to (a) punch the card for placing the desired code therein or (b) raise the selector bars in preparation for a sorting operation. After all digits have been entered, thereby activating all of the appropriate solenoids for representing the desired number, a further means may be actuated to concurrently enter the decimal code in the next field and then activate the apparatus, that is either the punching apparatus or the sorting apparatus, depending upon the desired mode of operation.

Thus, it is an object of this invention to provide a new and improved coding system for data members.

It is another object of this invention to provide a new and improved method and apparatus for encoding data members such as edge notched cards and the like using a decimal code in addition to numerical codes for improved discrimination of selected data members from the remaining data members of a group.

It is another object of this invention to provide a new and improved method and apparatus for sensing selected data members such as edge notched cards and the like relative to the remaining data members of a group.

It is another object of this invention to provide a new and improved means employing a common input member for encoding and/or sensing members at various field positions of a data member through a stepping switch.

Other objects and the attendant advantages of the present invention will become apparent from the detailed description to follow, together with the accompanying drawings.

BRIEF DESCRIPTION OF THE DRAWINGS

There follows a detailed description, to be read together with the accompanying drawings. However, it is to be understood that the description and the drawings are provided only to illustrate a preferred embodiment of the invention and that modifications and variations are apparent to those skilled in the art.

FIG. 1 is a table illustrating a code of the present invention.

FIG. 2 illustrates a data card showing a feature of the coding system of the present invention.

FIGS. 3, 4 and 5 each show a portion of a data card similar to that shown in FIG. 2, and each illustrates the new coding system of the present invention.

FIG. 6 illustrates the relative position of the data cards shown in FIGS. 3, 4 and 5 during a sorting operation.

FIG. 7 is a schematic view of a circuit which can be used for encoding and sensing, using the coding system of the present invention.

FIG. 8 is another schematic diagram showing a portion of the circuit of FIG. 7 in combination with a portion of a card encoding and sorting apparatus.

DETAILED DESCRIPTION OF THE PREFERRED EMBODIMENT

Referring now to the figures, like elements represent like numerals throughout the several views.

FIG. 1 is a table illustrating the coding system used in the present invention. In the example of an edge notched card, the card may have a plurality of field positions along its said edge, each field position having five bit positions. As can be seen from FIG. 1, different combinations of two of the five bits are used to represent each one of the 10 digits. The decimal is then represented by three of the five bits.

FIGS. 2 through 6 illustrate the application of the invention to an edge notched card 10. FIG. 2 illustrates the entire card which has eleven possible field positions represented by Roman numerals I through XI. Each field position is in turn subdivided into five bit positions. In FIG. 2 the first field position I is shown broken down into five bit positions A through E.

When encoding cards of this type, the first digit is normally encoded in the first field I. Subsequent digits of the number would then be encoded in subsequent adjacent fields. FIGS. 3 through 5 represent cards encoded with the numbers 4, 40 and 400, respectively. In each case the decimal code is entered into the field next adjacent the last digit of the numeral.

In the absence of the decimal code, a system attempting to select only card number 4 would also select the cards 40 and 400. This is because the apparatus attempting to select card 4 would raise selector bars corresponding to bit positions C and E in field member I. All remaining selector bars would remain in the recessed position. Thus, it can be seen that there would be nothing to prevent the cards shown in FIGS. 4 and 5 from moving onto the selector bars along with the desired card of FIG. 3.

This problem is eliminated by the feature of the present invention wherein the decimal code is entered into the field next following the last digit of the number for which the card has been coded. In operation in a sorting apparatus, selector bars are raised not only for the numbers themselves but also for the three bit positions of the decimal code. FIG. 6 illustrates how a card coded as shown in FIG. 3 (shown in dotted lines in FIG. 6) would be selected to the exclusion of all other cards such as those shown in FIGS. 4 and 5 (shown in dotted lines in FIG. 6). Selector bars 50 are raised at field position I at bit positions C and E for the number 4. Without more, any card starting with a 4 would also drop onto the selector bars 50. However, according to the present invention, the decimal code is applied at field position II, causing the three selector bars 51 to be raised at field position II at bit positions B, C and D. As is apparent from FIG. 1, there are no digits utilizing all three bit positions B, C and D. Thus, the raised selector bars in FIG. 6 will clearly eliminate all cards except those specifically coded for the number 4.

FIGS. 7 and 8 illustrate a preferred embodiment for encoding and selecting data members such as data cards in accordance with the features of the present invention.

First, the right-hand side of FIG. 8 illustrates, schematically, the relevant portion of a card punching and sorting apparatus which is explained in greater detail in our said copending application.

In an apparatus of the present type, a selector bar is provided for each of the bit positions. In the present case, since there are 11 fields, each with five bit positions, there would be 55 selector bars. The first 15 of these selector bars, that is the selector bars for fields I through III are shown at 40 in FIG. 8. These selector bars pass through a first portion 42 whereat card sorting takes place and a second portion 41 whereat edge punching of a card takes place in order to apply a given code to a card. Each selector bar includes a solenoid for selectively moving the same in its longitudinal direction. The solenoids for positions A through E for each of the first three field positions are shown in FIG. 8. A typical card 10, shown from above, is also shown in FIG. 8.

Whether cards are to be sorted or punched, the first step is to move the appropriate selector bars to the right (as viewed in FIG. 8). The selector bars of FIG. 8 have been set for the number "40." Note that the bars moved to the right in each of the first three field positions correspond to the notches shown

in FIG. 4. For punching, a card would be placed into the area 41 as shown in FIG. 8 and the punching apparatus would act through the selector bars moved to the right to effect appropriate punching of the card as explained in greater detail in our said copending application. On the other hand, if it is desired to select and sort out the cards with the number "40" thereon, then the apparatus for the sorting area 42 would then be operated to lift the selector bars which have been moved to the right and to complete the cycle of operation as explained in the said previous copending application.

The left-hand side of FIG. 8 shows three of the five stepping switches shown in FIG. 7. The other two stepping switches have been deleted for purposes of clarity since it is believed that the principle of operation of the invention is clear from the illustrated switch.

Referring now to FIG. 7, there is provided a plurality of stepping switches 12 through 16 each capable of moving the system through eleven positions corresponding to the eleven field positions. The switches are now located at the field position number III. Each of the stepping switches 12 through 16 have been associated therewith, respectively, solenoids 17 through 21 representing bit positions A through E, respectively. FIG. 7 shows only a single solenoid connected to each stepping switch. In practice, there would be one line to each of the "A" solenoids in each of the eleven field positions. Three of these leads from each of the stepping switches 12, 13 and 14 are shown in FIG. 8. Of course there would be an additional lead for each of the remaining field positions IV through XI. However, these have been deleted even from FIG. 8 for purposes of clarity.

At the left side of FIG. 7 there is shown a representation for a keyboard having buttons for each of the digits "1" through "0." Lines are directed from these buttons through lines 31 to the stepping switch 12, through lines 32 to the stepping switch 13, through lines 34 to the stepping switch 14, through lines 35 to the stepping switch 15, and through lines 36 to the stepping switch 16. These lines are connected to energize the respective solenoids for bit positions A through E in precisely the manner as illustrated in the table of FIG. 1. For example, the number "1" should energize solenoids for bit positions A through E. Thus, it will be seen that lines from button number "1" lead through lines 31 and 36 to stepping switches 12 and 16 for energizing solenoids A and E respectively. All buttons 40 also direct current along an additional line 33. This completes the circuit through the stepping relay 26, thereby energizing it. When the button of keyboard 11 is then released, the energized stepping relay deenergizes causing movement of the stepping switches 12 through 16 to the next field position.

After all digits have been entered into the keyboard, the cycle switch 22 is depressed. This closes the circuit through lines 25 to energize solenoids 18, 19 and 20 to enter the decimal into the field position next following that of the last digit. Simultaneously current through lines 53 and 54 energizes the stepping relay switch 26 and the holding relay 27, respectively. The stepping relay 26 closes stepping relay controlled contact 24 and the holding relay closes holding relay controlled contacts 23 and 29. Meanwhile, of course, the homing switch 28 is closed. With the holding contacts 23 and 29 closed, a holding circuit is formed through line 55 to the holding relay 27 and through lines 55 and 54 and through switches 23 and 24 to the stepping relay 26. Consequently, the cycle switch 22 may now be released. The stepping switch now steps through a complete cycle back to its original position at field I, ready for the next sorting or coding operation. Finally, movement of the stepping switches to their said original positions at field position I cams out, that is opens the homing switch 28, thereby breaking the circuit, deenergizing the relays 26 and 27 and hence opening the contacts 23, 24, and 25. Switch 28 may be opened just long enough to cause opening of the said contacts or, alternatively switch 28 may be mechanically connected to the stepping switches to be opened when the said stepping switches are at field position I and to be closed as soon as the stepping switches move to any other field

position. A further contact 56 may be provided and operated by the circuit, for example it may be closed upon deenergization of relay 27, for commencing operation of a card sorting or a card punching operation.

Although the invention has been described in considerable detail with respect to a preferred embodiment thereof, it will be apparent that the invention is capable of numerous modifications and variations apparent to those skilled in the art without departing from the spirit and scope of the invention.

I claim:

1. A method of encoding a card having a plurality of useable positions located along one edge of the card with a code representing a series of symbols comprising the steps of:

punching notches in the edge of the card in said useable positions to encode the card such that the notches represent the series of symbols.

regardless of the number of positions encoded to represent the series of symbols, encoding the position next following the position of the last of said symbols with a code representing a decimal point.

2. A method according to claim 1 wherein each symbol of the series of symbols is represented by a pair of notches and the decimal point is represented by a group of three notches.

3. A method of encoding a card having a series of encoding positions located along one edge of the card, the step of en-

25
5 coding comprising punching notches in the encoding positions on the card, the code representing at least (a) a selected one of the digits of the decimal numbering system and (b) a decimal; and wherein each digit of the decimal system is represented by a different group of two notches and wherein the decimal is represented by a group of three notches.

4. An apparatus for encoding a card having a series of encoding positions located along one edge of the card, means for coding the card comprising means for punching notches in the 10 edge of the card, encoding positions on the card being notched with a code including a different pair of notches representative of each digit, and means for encoding a decimal comprising means for punching three notches in the edge of the card, the decimal being encoded in the card following the 15 encoding of the last digit regardless of the number of digits encoded.

5. An apparatus according to claim 4 including a common input means for entering the code into the apparatus and a stepping switch for connecting said common input means to 20 successive encoding positions.

6. An apparatus according to claim 5 including means for operating said switching means automatically, following the input of a code to an encoding position to connect the input means to the next successive encoding position.
